[57] **CLAIM**

The ornamental design for a combined modular display rack and lighting fixtures unit, as shown and described.

DESCRIPTION

FIG. 1 is a left front perspective view of a combined modular display rack and lighting fixtures unit showing my new design with the diagonal wires drawn as single lines for clarity;

FIG. 2 is a left side elevational view thereof;

FIG. 3 is a top plan view thereof with the diagonal wires drawn as single lines for clarity;

FIG. 4 is a rear elevational view thereof with the diagonal wires drawn as single lines for clarity.

Fig. 1
